HEAT TRANSMITTING TUBE OF STEAM GENERATORS

Filed Oct. 16, 1924

Inventor:

Zeger Jan Hendrik Jonker.

By Enay, Borch, Janney & Enay.

Attorneys.

UNITED STATES PATENT OFFICE.

ZEGER JAN HENDRIK JONKER, OF HILVERSUM, NETHERLANDS.

HEAT-TRANSMITTING TUBE OF STEAM GENERATORS.

Application filed October 16, 1924, Serial No. 743,933, and in Netherlands November 30, 1923.

The present invention relates to improvements in or modifications of the improved heat transmitting tubes of steam generators as set forth in the American application Ser.

5 No. 599,870 filed November 9, 1922.

In accordance with the invention the improvements chiefly consist in that the return tube which leads into the main tube within the boiler space through an opening 10 in the lower end thereof, is prolonged down to the bottom and is arranged concentrically within said main tube, whilst the lowermost extremity of the return tube is closed and is provided with holes in it.

15 This improved construction in use has the advantage that when the fire comes in contact with the main tubes, whereby the formation of steam through radiation from a large tube surface is considerably increased, no risk of dryness of the main tube 20 and consequent explosion thereof need be feared.

An example of construction of the invention is shown in the accompanying drawing, 25 being a part sectional elevation through a main tube with return tube.

The boiler with its bottom plate 1 and furnace 2 contains a plurality of sealed tubes which are secured to the bottom plate 30 1 of the boiler by means of a threaded ferrule 7. The lower portion 3 of the tube projects into the furnace whilst the upper portion 4 is disposed in the interior of the boiler. The return tube 6 which branches off the 35 head of the main tube and runs along it, leads into the main tube in the lower part of the boiler and runs concentrically within it to the bottom thereof.

The return tube is closed at its lowermost 40 extremity but is provided, however, with holes 8 arranged around it. In order to increase the conduction of heat to the boiler water, the portions of the tubes projecting within the boiler are provided with fins 9.

45 The action is as follows:

The flames of the fire contact with those parts of the tubes disposed within the furnace whilst these parts are also heated by radiation from the furnace. The liquid contained in the sealed tubes is evaporated, 50 steam rising in that portion of the tube which is disposed within the boiler and

transmitting its heat to the boiler water, whilst the condensed steam returns through the return tube 6 back into the main tube 55 through the holes 8.

To prevent the heated liquid from rising within the return tube 6, the latter is closed at its lowermost extremity, whilst the upward movement of the heated liquid is so 60 rapid as to cause it to pass by the holes 8.

Claims:

1. In an apparatus of the class described, a furnace chamber; a boiler chamber; means separating said chambers; a sealed heat-transmitting tube having its lower end located in said furnace chamber and its upper portion in said boiler chamber; and a return tube for the water of condensation leading from the upper end of said heat-transmitting tube outside the upper portion of the latter to the lower portion thereof, and passing through the outer wall of said heat-transmitting tube in the lower end of said boiler chamber and extending therebeyond 75 within the lower end portion of said heat-transmitting tube in the furnace chamber, the lower end of said return tube being closed and the lateral wall of said return tube being apertured above said closed lower 80 end.

2. In an apparatus of the class described, a furnace chamber; a boiler chamber; means separating said chambers; a sealed heat-transmitting tube having its lower end located in said furnace chamber and its upper portion in said boiler chamber; a return tube for the water of condensation leading from the upper end of said heat-transmitting tube outside the upper portion of the 90 latter to the lower portion thereof and passing through the outer wall of said heat-transmitting tube in the lower end of said boiler chamber and extending therebeyond 95 within the lower end portion of said heat-transmitting tube in the furnace chamber, the lower end of said return tube being closed and the lateral wall of said return tube being apertured above said closed lower end, and a plurality of longitudinal ribs about said heat-transmitting tube within

100 said boiler chamber.

3. In an apparatus of the class described, the combination of means presenting a fur-

nace chamber; a boiler chamber; a wall separating said chambers; a sealed heat-transmitting tube extending through said wall; and a condensation return tube leading from the upper portion of said heat-transmitting tube, first externally of, thence through the lateral wall of said transmitting tube to the interior of the latter above

said separating wall, and thence to a point below said separating wall, the lower end of said return tube being closed, and the lateral wall of said return tube above said closed end being apertured.

In testimony whereof, I have signed my name to this specification.

Z. J. H. JONKER.
